LIQUID CONDUCTOR HEATER

Marshall W. Hanks, Madison, Wis., assignor to
 HanksCraft Company, Madison, Wis., a corpora-
 tion of Wisconsin

Application February 16, 1938, Serial No. 190,816

7 Claims. (Cl. 219—40)

This invention relates to improvements in liquid conductor heaters of the type disclosed, for example, in the United States Patent No. 1,683,071, granted to Marshall W. Hanks and Max Mason on September 4, 1928, in which a pair of spaced electrodes connected in an electric circuit are located in a vessel of insulating material and adapted to be connected by a measured quantity of water or other vaporizable liquid which is adapted to be heated, and evaporated to substantial dryness, by the passage of current therethrough, thus giving the apparatus a substantially definite time period of operation. By suitably regulating the measured quantity of liquid which is put into the vessel, the duration of the operation of the apparatus may be varied as desired. The apparatus of the present invention may be used for warming a baby's milk bottle, or for cooking eggs, or for heating or cooking various other objects for definite time periods which are automatically terminated by the evaporation of the liquid, without attention on the part of the operator, but the invention is disclosed herein as being applied to a milk bottle warmer of the type described and claimed in my copending application Serial No. 156,159, filed July 28, 1937.

In the construction and use of liquid conductor heaters of the type referred to it is common practice to connect the spaced electrodes to the terminals of an electric circuit by a flexible electric cord comprising a pair of conductors twisted together and having their extremities connected to the electrodes beneath the vessel. It has been found that the heat developed in the apparatus, by the passage of current between the electrodes causes a rise in the temperature of the conductors of the electric cord considerably above that produced by the normal passage of electric current therethrough with the result that such apparatus has in some instances been regarded as a fire hazard and it has been difficult to obtain its approval under all circumstances by fire insurance underwriters, and the like.

The principal object of the present invention is to overcome the above mentioned difficulty by providing an improved liquid conductor heater of the type referred to comprising means for preventing the undue rise in temperature of the supply conductors. A further object is to provide a liquid conductor comprising a vessel of insulating material provided with a cavity or well which serves as a trap to prevent the conduction of heat from the electrodes and the

heated liquid to the supply conductors which are connected to the electrodes. Still another object of the invention is to provide a liquid conductor heater comprising improved means for interlocking the supply conductors with parts of the insulating vessel in which the spaced electrodes are located, to relieve strain upon the connections between the conductors and the electrodes, in combination with means for preventing the abnormal rise of temperature of the conductors adjacent to the point or points where they are interlocked with the vessel. Other objects relate to various features of construction and arrangement which will appear more fully hereinafter.

The nature of the invention will be understood from the following specification taken with the accompanying drawings in which one embodiment is illustrated. In the drawings,

Fig. 1 shows a perspective view of one form of the improved liquid conductor heater of the present invention, which is shown as being used for heating a baby's milk bottle;

Fig. 2 shows an enlarged top plan view of the liquid conductor heater shown in Fig. 1 with the milk bottle removed;

Fig. 3 shows a vertical section taken on the line 3—3 of Fig. 2;

Fig. 4 shows a vertical section taken on the line 4—4 of Fig. 2;

Fig. 5 shows a horizontal section taken on the line 5—5 of Fig. 3;

Fig. 6 shows an enlarged top plan view of the nut or washer which is engaged by a bolt by which the insulating plate is held above the electrodes;

Fig. 7 shows an enlarged bottom plan view of the electric conductor heater shown in Fig. 1 with a portion of the bottom cover plate or name plate removed;

Fig. 8 shows a side elevation of the insulating plate which is mounted over the electrodes;

Fig. 9 shows a bottom plan view of the insulating plate shown in Fig. 8;

Fig. 10 is an enlarged vertical sectional view taken on the line 10—10 of Fig. 7, showing the well or cavity which prevents the transfer of heat from the interior of the vessel to the supply conductors; and

Fig. 11 shows an enlarged vertical section of the line 11—11 of Fig. 7, illustrating the means for connecting the terminals of the electrodes with the supply conductors.

As illustrated in the drawings, the invention comprises a vessel 15 formed of porcelain or

other suitable insulating material which is adapted to receive the article or object to be heated or cooked. In this instance, a baby's milk bottle 16 is shown mounted in the cavity of the vessel. The vessel 15 has an outer annular wall 15^a, a bottom wall 15^b, and a lower annular flange or base portion 15^c adapted to rest upon a table or other support and forming a bottom cavity 15^d in which connections are established with a pair of spaced electrodes 17 and 18 which are located in the bottom of the vessel, resting on the bottom wall 15^b. The electrodes 17 and 18 are preferably formed as bare round wires of conducting material which are wound in spiral fashion and located one within the other so that convolutions of one electrode are located on opposite sides of each convolution of the other electrode. The convolutions of the separate electrodes are maintained in place laterally on the bottom wall 15^b and are spaced from adjacent convolutions of the other electrode by means of projections 15^e which are formed integrally with the bottom wall 15^b and which project upwardly therefrom. These projections 15^e are preferably arranged in rows extending radially outward from the center of the vessel as shown in Fig. 5.

The electrodes 17 and 18 are held in place on the bottom wall 15^b by means of an insulating plate 20 formed of porcelain or other suitable insulating material which rests upon the upper edges of the electrodes and which is secured in place by a bolt 21 engaging a nut 22 which is located in a recess 15^f formed in the upper surface of the bottom wall 15^b. The nut 22 is preferably in the form of a flat spring washer as shown in Fig. 6, being notched on one side as shown at 22^a. This washer is of a diameter slightly greater than the diameter of the upper part of the circular recess 15^f in the bottom wall of the vessel, and the central aperture 22^b in this washer is of a diameter such that it fits the bottoms of the spaces between the threads of the bolt, so that the washer forms a one-thread nut. When this washer is pushed downwardly into the recess 15^f, it assumes a downwardly convexed shape and is retained in the recess by the engagement with the wall thereof and the extremity of the bolt 21 may be threaded into engagement therewith to hold the insulating plate 20 in tight engagement with the electrodes 17 and 18 so that these electrodes are clamped against the bottom wall of the vessel.

The insulating cover plate 20 is provided on its upper side with a central annular surface 20^a and three outwardly radiating surfaces 20^b which are horizontal and which are adapted to be engaged by the bottom of the milk bottle 16. The portions of the insulating plate between the horizontally radiating flat portions 20^b are inclined downwardly as shown at 20^c, forming radiating troughs 20^d. These troughs are inclined downwardly and outwardly so that any water or other vaporizable liquid on the upper surface of the insulating plate is directed downwardly by gravity and flows from the troughs 20^d to the bottom of the vessel where it engages the spaced electrodes 17 and 18. This is of particular importance when the apparatus is being operated with a relatively small quantity of water or other liquids, as it is desirable that all portions of this liquid reach the electrodes to be heated and vaporized, thus giving the apparatus a definite time period of operation. The head of the bolt 21 is located in a central recess or de-

pression 20^e formed in the upper side of the insulating plate and the stem of the bolt extends through a central boss 20^f from which three flanges or arms 20^g extend radially outward, being united integrally with the under side of the body of the plate. These flanges or arms 20^g are preferably located directly beneath the flat portions 20^b upon which the bottle 16 rests, and the lower edges of these flanges 20^g are adapted to engage the upper edge portions of the electrodes 17 and 18 which are thus clamped between the flanges and the bottom wall 15^b of the vessel. The flanges or arms 20^g thus form the cavities 20^h which are open at their outer ends and which serve as boiling spaces immediately above the electrodes so that there is a free opportunity for bubble formation as the liquid in the vessel is heated and vaporized. The plate 20 is preferably slightly less in diameter than the internal diameter of the lower portion of the cavity of the vessel 15 so that there is an annular space 23 around the outer edge of the plate 20 to permit the upward escape of bubbles which are produced by the heating of the liquid. In addition, the ready escape of these bubbles is insured by the provision in the body portion of the plate 20 of a number of apertures 20ⁱ which are preferably located in the inclined portions 20^c of the troughs, as shown in Fig. 2.

The electrodes 17 and 18 are connected in a supply circuit by having portions 17^a and 18^a thereof, respectively, led downwardly through apertures 15^b which are formed in the bottom wall of the vessel. After inserting these portions of the electrodes through the apertures 15^b, the apertures may be sealed by any suitable waterproof cement which is adapted to withstand any heat which may be generated by the passage of current through the electrodes. If desired, portions of rubber tubing may be inserted around the electrodes in the apertures before applying the cement. The extremities of the electrodes are connected to supply conductors 25 and 26 which are surrounded by insulation to form a common flexible cord 27 having at the end thereof a fitting 28, as shown in Fig. 1, which permits the connection of the conductors 25 and 26 in an electric circuit. In order to connect the extremities of the electrodes with the conductors 25 and 26, which have the insulation removed from the inner ends thereof, without the use of screws or other usual fastening means, the bottom wall 15^b of the vessel is provided on its underside with a pair of elongated grooves or recesses 15ⁱ which have their side walls tapered upwardly. The bare extremities of the conductors 25 and 26 are laid across these grooves and then, after placing the extremities 17^b and 18^b of the electrodes transversely across these extremities of the supply conductors, these portions 17^b and 18^b of the electrodes are pushed upwardly into the grooves 15ⁱ, thereby forming U-shaped bends in the extremities of the conductors 25 and 26, as shown in Fig. 11, and causing these conductors to be held in frictional engagement with the extremities of the electrodes. In order to compensate for various diameters of the wires and electrodes which may be employed with a particular vessel 15, shims 29 of any suitable material may be placed above the conductors 25 and 26 before the parts are pushed into the grooves 15ⁱ, as shown in Fig. 11, and the shims may be selected of any suitable thickness to cause a tight wedging fit when the parts have been pushed into the grooves. The con-

ductors 25 and 26 may be prevented from shifting laterally adjacent the grooves 18^a by providing bosses 15^b on the underside of the bottom wall 15^b of the vessel, as shown in Fig. 7, these bosses being located in pairs and spaced apart to receive one of the conductors between them.

For the purpose of locking the insulated portions of the conductors 25 and 26 to prevent any tension created in the cord 27 from being transmitted to the connections which are formed between these conductors and the electrodes, the conductors 25 and 26 are bent transversely adjacent the aperture 15^k through which the supply core 27 is brought in through the base flange 15^c of the vessel, and the bottom wall of the vessel is provided with two locking lugs 18ⁱ which are formed integrally with this wall and which extend downwardly at opposite sides of the axis of the aperture 15^k so that the conductors 25 and 26, in passing around these lugs 18ⁱ are compelled to make sharp bends with respect to the cord 27 preliminary to being attached to the electrodes, as shown in Fig. 7. In addition, the two conductors 25 and 26 may be knotted together just inside of the aperture 15^k, as shown by dotted lines at 27^a thus providing an enlargement of larger area than the aperture 15^k so that any longitudinal strain on the cord 27 is transmitted by the knot 27^a to the base flange 15^c of the vessel. Without this knot 27^a, the angular disposition of the portions of the containers 25 and 26, which are positioned just inside of the aperture 15^k, will prevent undue strain from being transmitted to the connections between the conductors and the electrodes.

For the purpose of preventing undue heating of the conductors 25 and 26 in the region of the bottom wall of the vessel, the vessel 15 is provided with an upwardly extending cavity or well 15^m which is arcuate in cross section, both horizontally and vertically, as illustrated in Figs. 7 and 10, the outer wall of this cavity forming an upward continuation of the inner surface of the base flange 15^c of the vessel and the inner wall of the cavity extending concentric with the inner wall of the vessel, thus forming an air space extending horizontally beyond the portions of the conductors 25 and 26 which are passed around the lugs 18ⁱ while at the same time extending vertically to a considerable degree above those portions of the conductors which pass through the aperture 15^k. An opening 15ⁿ is preferably provided leading outwardly to the atmosphere from the upper part of the cavity to permit a free circulation of air through the cavity. This air space serves as a heat insulator to prevent the transfer of heat from the interior of the vessel to the conductors 25 and 26 in the cord 27 where it passes through the aperture 15^k, thus bringing about a substantial reduction in the temperature of those portions of the conductors 25 and 26 which lie beneath the vessel, and, in particular, of that portion of the cord 27 which lies within the aperture 15^k. This reduction in temperature is sufficient to remove all danger of heating to the point where combustion would take place and has led to the approval of a device of this kind for use under all circumstances.

The connections of the supply conductors with the electrodes are preferably concealed by a cover plate 30, formed of suitable sheet metal or the like, which seats against the annular shoulder 15^r formed on the inner portion of the base

- flange of the vessel. In order that this cover plate may be secured to the vessel without use of screws or other similar fastening means, the base of the vessel is provided with a projecting boss 15° against which the cover plate 30 is adapted to seat and this boss is provided with a downwardly extending stud 15^p, which may be circular in cross section, and which is preferably provided around its outer surface with a plurality of vertically extending ribs or serrations 15^q which are adapted to bite into the wall of a circular aperture 30^a formed in the plate 30. When the plate is driven upwardly over the stud 15^p, the metal will interlock with the porcelain of the boss 15° and thus hold the plate in place. This cover plate 30 may serve as a name plate for the manufacturer and also to carry printed directions for the operation of the apparatus.
- Although one form of the invention has been shown and described by way of illustration, it will be understood that it may be constructed in various other embodiments coming within the scope of the appended claims.
- 25 I claim:
1. A liquid conductor heater comprising an insulating vessel adapted to contain a measured quantity of liquid, a pair of spaced electrodes in said vessel adapted to be connected by said liquid, said vessel having a bottom wall with a continuous annular flange extending downwardly therefrom to rest upon a support, said flange having an aperture therethrough communicating with the space beneath said bottom wall, and a pair of electric supply conductors leading through said aperture and connected to said electrodes, said insulating vessel having a cavity therein extending upwardly from the region of said conductors and positioned to limit the transfer of heat from the interior of said vessel to said conductors in the vicinity of said aperture.
  2. A liquid conductor heater comprising a vessel of insulating material having a chamber adapted to contain a measured quantity of liquid, a pair of spaced electrodes in said chamber adapted to be connected by said liquid, said vessel having a bottom wall and a continuous annular base flange extending downwardly below said bottom wall to rest upon a support, said flange having an aperture therethrough communicating with the space beneath said bottom wall, and a pair of electric supply conductors leading through said aperture and having connections with said electrodes, said vessel having a cavity therein leading upwardly from said conductors within the upward projection of the area enclosed by said base flange and positioned with its upper part horizontally outward from the lower part of said chamber.
  3. A liquid conductor heater comprising a vessel of insulating material having a chamber adapted to contain a measured quantity of liquid, a pair of spaced electrodes in said chamber adapted to be connected by said liquid, and a pair of electric supply conductors having connections with said electrodes, said vessel having a supporting base flange provided with an aperture through which said conductors extend and having a cavity extending upwardly from said conductors inside the said base flange and horizontally outward from said chamber, said vessel having a ventilating opening leading outwardly to the atmosphere from the upper part of said cavity.
  4. A liquid conductor heater comprising a ves-

sel of insulating material having a chamber adapted to contain a measured quantity of liquid, a pair of spaced electrodes in said chamber adapted to be connected by said liquid, and a pair of electric supply conductors having connections with said electrodes, said vessel having an annular supporting base flange provided with an aperture through which said conductors extend and having a cavity extending upwardly from said conductors inside the area enclosed by the said base flange and positioned horizontally outward from a part of said chamber, said cavity being arcuate in cross section both horizontally and vertically, said vessel having an opening leading outwardly to the atmosphere from the upper part of said cavity.

5. A liquid conductor heater comprising a vessel of insulating material having a chamber adapted to contain a liquid, a pair of spaced electrodes in said chamber adapted to be connected by said liquid, said vessel having a bottom wall and an annular supporting flange extending downwardly therefrom, said flange having an aperture therein, a pair of electric supply conductors leading through said aperture and positioned adjacent said bottom wall, said conductors and said electrodes having connections through said bottom wall, and insulating posts carried by said bottom wall to spread said conductors apart within said flange, said vessel having a cavity extending upwardly from said conductors in the region between said flange and said posts to effect the cooling of said conductors.

6. A liquid conductor heater comprising a vessel of insulating material having a chamber adapted to contain a liquid, a pair of spaced electrodes in said chamber adapted to be con-

nected by said liquid, said vessel having a bottom wall and an annular supporting flange extending downwardly therefrom, said flange having an aperture therein, a pair of electric supply conductors leading through said aperture and positioned adjacent said bottom wall, said conductors and said electrodes having connections through said bottom wall, and insulating posts carried by said bottom wall to spread said conductors apart within said flange, said vessel having a cavity extending upwardly from said conductors in the region between said flange and said posts to effect the cooling of said conductors, said cavity being located in the outer wall of said chamber and said vessel having a ventilating opening extending outwardly from the upper part of said cavity.

7. A liquid conductor heater comprising a vessel of insulating material having a chamber adapted to contain a liquid, a pair of spaced electrodes in said chamber adapted to be connected by said liquid, said vessel having a bottom wall and an annular supporting flange extending downwardly therefrom, said flange having an aperture therein, and a pair of electric supply conductors leading through said aperture and positioned adjacent said bottom wall, said conductors and said electrodes having connections through said bottom wall, said conductors being knotted within said aperture to prevent longitudinal strains thereon from being transmitted to said connections, said vessel having a cavity therein extending upwardly in the wall thereof in the region of said knot to effect the cooling of said conductors.

MARSHALL W. HANKS.
